UNITED STATES PATENT OFFICE.

ALVAH P. OSBORN, OF TRUMANSBURG, NEW YORK, ASSIGNOR TO ORNAN OSBORN, OF SAME PLACE.

SULKY-PLOW.

SPECIFICATION forming part of Letters Patent No. 257,749, dated May 9, 1882.

Application filed December 9, 1881. (No model.)

To all whom it may concern:

Be it known that I, ALVAH P. OSBORN, a citizen of the United States, residing at Trumansburg, in the county of Tompkins and State of New York, have invented certain new and useful Improvements in Sulky-Plows, of which the following is a specification, reference being had therein to the accompanying drawings.

10 This invention has relation to sulky-plows; and the novelty consists in pivoting the plow-beam to the frame so that it may have a free lateral movement on each side of a locked position which corresponds to the line of draft.

15 It further consists in pivoting the beam to the axis to admit of a vertical motion, combined with mechanism whereby the plow may be raised or lowered at will, and so arranged that the plow and its beam will ride over an 20 obstruction without operating or affecting the raising and lowering mechanism, as will be hereinafter set forth.

Figure 1 is a top plan view of my sulky-
w; Fig. 2, a side elevation thereof with
25 the near wheel removed. Figs. 3 and 4 are
details of the locking device. Fig. 5 is a side
elevation, showing more clearly the plow-
lifting mechanism; and Fig. 6 is a similar
30 view, in which is illustrated the manner in
which the plow will ride over an obstruction
without changing the position of the lifting
mechanism.

In the accompanying drawings, similar letters of reference marked thereon indicate like
35 parts of the invention.

A is the plow-beam, provided with the usual
point, B, and mold-board C.

D is the arched axle, to the outer ends of
40 which are secured the cranks E E', carrying
the wheels F F'.

To the forward end of the beam A is at-
tached the ordinary clevis, G.

H is the tongue, which is secured in a shoe
cast on the axle D.

45 I is a spring-seat for the driver, and is se-
cured to the tongue H by bolts i.

K is a clutch mounted upon a shaft, L, pass-
ing through the arch D, its ends extending
outward so as to form journals for the wheel-

cranks E E'. In the front end of the clutch 50
K is a detent, k, and extending rearward is
an angular arm, M. A yoke, N, is cast on the
clutch K, and extends downward and around
the beam A. A locking-lever, O, is secured
on top of the forward end of the beam and 55
within reach of the driver's foot. One end of
this lever O engages in the detent k of the
clutch K, and is held securely there by the
spring o. A dog, o', on this lever drops into
a depression in the beam and prevents the 60
strain coming on the shaft o', upon which the
lever is mounted.

A hand-lever, P, is secured to the tongue,
and connected by the usual chain and rod to
a bent crank, R, mounted on the shaft L. This 65
crank R passes under the arm M, but is not
connected to it, so that if the lever P is op-
erated the arm M and clutch K will be tilted,
and at the same time the arm and clutch may
be raised, by the action of the plow passing 70
over an obstruction, without interfering with
or moving the crank R and its connecting mech-
anism.

The plow-beam is pivoted in the yoke N by
the bolt n. When the lever O is in the detent 75
k the beam A is rigid with the frame so far as
lateral motion is concerned; but of course the
beam may be vertically raised or lowered by
the lever P.

The plow proper being in the position shown 80
in Fig. 1, and it being necessary to turn, say,
a right angle, in plowing, the driver presses
his foot on the forward end of the foot-lever O,
which releases it from the detent k in clutch
K, and by turning the tongue to the right or 85
left the plow-beam remains fast, being held
by the point in the furrow. The driver then
starts the team in the new direction, which
causes the beam to swing around until it comes
into the new line of draft, and as soon as it does 90
the detent k is brought in line with the lever
O, which falls into it and locks it in said posi-
tion.

It will thus be seen that it is not necessary
for the driver to raise the plow from the fur- 95
row in turning a corner, or to lock it after he
does turn, as this is accomplished automatically.

It will also be observed that the mechanism

for raising the plow in traveling from one field to another is not affected when the plow-point strikes an obstruction.

I am aware previous to my invention locking devices have been applied to the tongue and frame of wheel plows and cultivators, whereby the tongue may swing on either side and lock itself on returning to its normal position. My improvement relates only to devices for automatically locking the plow-beam in the direction of the line of draft and releasing it when turning corners.

Having thus fully described my invention, what I claim as new and useful, and desire to secure by Letters Patent of the United States, is—

1. The combination, in a sulky-plow, of a plow-beam vertically pivoted to the frame, and mechanism for automatically locking it in a position corresponding to the line of draft, substantially as and for the purpose set forth.

2. The combination, in a sulky-plow, of a plow-beam pivoted to the frame forward of the point of the plow, and mechanism for auto-

matically locking it in a position corresponding to the line of draft and releasing it therefrom at the will of the operator, as set forth.

3. In a sulky-plow, a vertically-pivoted plow-beam provided with a locking-lever, combined with a frame having a catch to receive the locking-lever, whereby the beam may be automatically locked in position, substantially as and for the purpose set forth.

4. In a sulky-plow, the beam A, having the locking foot-lever O, in combination with the shaft L, arch-axle D, clutch K, having detent k, and yoke N, substantially as and for the purpose set forth.

5. In a sulky-plow, the beam A, secured to the clutch K, having the arm M, in combination with the crank R and hand-lever P, substantially as and for the purpose set forth.

In testimony whereof I affix my signature in presence of two witnesses.

ALVAH P. OSBORN.
